(57) **CLAIM**

The ornamental design for pair of wireless earbuds, as shown and described.

DESCRIPTION

FIG. 1 is a perspective view of the pair of wireless earbuds showing my new design;

FIG. 2 is a left side view of the pair of wireless earbuds;
FIG. 3 is a right side view of the pair of wireless earbuds;
FIG. 4 is a front view of one earbud of the pair of wireless earbuds; the other earbud is a mirror image;
FIG. 5 is a rear view of one earbud of the pair of wireless earbuds; the other earbud is a mirror image;
FIG. 6 is a top view of the pair of wireless earbuds; and,
FIG. 7 is a bottom view of the pair of wireless earbuds.
The broken lines in the drawings depict portions of the pair of wireless earbuds that form no part of the claimed design.
